UNITED STATES PATENT OFFICE.

BRADFORD BORDEN, OF CLEVELAND, OHIO.

THREAD-CUTTING TOOL.

Application filed March 23, 1925. Serial No. 17,737.

The pipe threading tool forming the subject-matter of the present invention has been designed particularly with a view to the cutting of various sized work with but one set of dies and without necessitating the removal of the dies from the stock. The invention contemplates among other things a construction wherein the dies may be quickly and accurately set for different sized work even in a poorly lighted shop, and which once having been set will be effectively held in set position against accidental movement during the manipulation of the tool either in the threading operation or in the changing from one piece of work to another.

Other objects of the invention are to provide a slidable support for each die which is controlled in a movement toward and from the axis of the work by the movement of the die stock; to furnish an adjusting means for each die and a novel connection between said adjusting means and die whereby the same will not become separated while in use, and generally to provide a construction which will be of a very simple and durable nature and highly efficient in practical use.

The various features of novelty which characterize my invention are pointed out with particularity in the claims annexed to and forming a part of this specification. For a better understanding of the invention, however, reference should be had to the accompanying drawings in connection with the following descriptive matter, the drawings depicting what I now regard as a preferred embodiment of the invention.

In the drawings, wherein like reference characters denote like parts throughout all views,

Figure 1 is a top plan view of a diestock embodying my invention;

Figure 2 is an elevation;

Figure 3 is a fragmentary vertical sectional view;

Figure 4 is a section on the line 4-4 of Fig. 3;

Figure 5 is a section on the line 5-5 of Fig. 4;

Figure 6 is an inner end view of one of the slideways;

Figure 7 is a perspective detail of a washer, and

Figure 8 is a sectional view similar to Figure 3 illustrating a modification.

Referring specifically to the drawings, the numeral 1 denotes a work holder which may be of any preferred type, the same being provided with a shouldered neck portion 2 which surrounds the work receiving opening and supports an annulus or plate 3 from which rise posts 4, the same being slidably received in holes extending transversely through the longitudinally slotted bosses 6 of the die stock 5. A ring 7 threaded upon the neck 2 of the work holder serves to retain the annulus 3 against displacement but permitting rotation thereof. The inner portion of the neck 2 is threaded for the reception of the leader screw 8 carried by the die stock 5 whereby the latter will be progressively moved in the direction of the work holder as the threading operation progresses. This is a well known and familiar construction in the art.

The slots or slideways 9 in the bosses 6 are radially arranged and communicate entirely through the said bosses from the work receiving opening of the die stocks. It is to be noted that the transverse post holes in the bosses 6 are so drilled as to intersect the slideways 9 adjacent one side; also that the posts 7 are provided with a flat longitudinal face the edges of which are designed to lie flush with the side wall of each slideway. The purpose of this construction will be fully explained hereinafter.

As clearly shown in Figure 3, the slideways 9 receive sliding die carriers 10 of a width equal to the width of the slideways and having upturned outer ends 10^a. The carriers 10 are designed to slidably and removably support dies or chasers 11, relative movement of each of which is controlled by means of a screw 12 threaded through an aperture in the upturned end 10^a of its carrier. The inner end of the screw 12 is formed with a head 12^a which is receivable in T-shaped slot 11^a extending crosswise of the die. Thus the movement of the die either toward or from the work receiving opening of the die stock is positively controlled by means of a set screw 12. It is to be noted that the head 12^a of the screw can only be located in the T-shaped slot 11^a of the die when the carrier is out of the slideway 9. When the die and carrier are in the slideway the side walls and overhanging top walls thereof engage the assembled members to prevent such relative movement as would permit disengagement of the same.

By adjustably positioning the dies 11 in the carriers 10 it is possible to thread work of different sizes with but one set of dies. A means has been availed of whereby the dies can be accurately set for threading standard sized work. This means comprises the formation of the outer portions of each screw shank without threads and cutting therein a plurality of circumferential grooves 12^b which are spaced certain distances the one from the other. This distance is equal to one-half of the difference between the diameters of standard sizes of pipe or other work. As shown in Figure 3, I have provided what might be termed a washer 13 having an over-sized opening to receive the screw 12. The washer is located between the thumb-piece 14 of the screw and the upstanding end portion 10^a of the carrier 10. When work of a certain size is to be threaded the washer is located in the appropriate groove 12^b and the screw advanced by means of the thumb-piece 14 until the washer snugly abuts against the outer face of the end of the carrier. This action causes the washer to bind in the groove in which it is located. Thus the screw will be locked against accidental turning and it will take a good firm twist on the thumb-piece 14 to loosen it, it being understood that the washer binds against the end of the die carrier and in the groove, which will obviously produce the result above set forth.

It has heretofore been stated that the posts 4 have flat faces which, during the movement of the die stock, lie flush with one of the side walls of each slideway 9. These flat post faces are denoted in the drawings by numeral 7^a, and in Figure 3 the said flat post faces are clearly shown as being formed with diagonal surface grooves 7^b arranged in a direction leading away from the axis of the work, the lower ends 7^c of such grooves being curved abruptly in a direction away from the axis of the work. The grooves 7^b are open at the upper ends of the said posts to receive lugs 15 extending from one side of each of the carriers 10. The grooves 7^b are designed to sustain the carriers 10 in the thread cutting operation; also to effect a gradual recession of the carriers as the operation proceeds, acting of course, through the lugs 15,— and finally through the instrumentality of the abruptly curved groove portions 7^c to precipitously actuate the carriers to completely withdraw the dies from the work.

When it is desired to move the carriers from the slideways 9 it is only necessary to elevate the die stocks on the posts a sufficient distance so that the lugs 15 of the carrier will be clear of the post grooves 7^b. The slides 10 can then, of course, be slipped out of the slideways 9. The posts 7 are of

sufficient length, as are also the grooves 7^b, to permit the diestock to be set at the start of the threading operation for cutting either a shallow or a deep thread, or for adapting the die teeth to engage either under or over 70 sized work. An adjustable stop 27 determines exactly the proper elevated position of the stock 5 when various odd sized work is to be threaded.

The die stock is rotated in the usual 75 manner by handles 16 received in sockets 17 carried at diametrically opposite points on the diestock. Upon one of the handles 16 I have illustrated a magazine for extra dies 11, the same comprehending fixed and sliding 80 collars 18 and 20. Circumferential flanges 18^a and 20^a, respectively, engage the ends of the dies 11 to hold them in place. A spring clip 21 engages notches 22 in the handle section to hold the collar 20 against 85 outward sliding movement. A pin 19 passing through the member 18 and the handle 16 maintains the said collar member 18 fixed.

In Figure 8 I have illustrated a slightly 90 modified construction whereby the screw 12' will be locked in a predetermined position. Here a spring clip 23 is fixed to the upturned end 10^a of the carrier 10' and has a depending portion 24 with an arcuate edge 95 recess which is designed to engage in a selected groove 12^b. Turning of the screw in either direction will be prevented by the binding of the clip portion 24 against the walls of the selected groove. In this modification the screw 12' has no positive connection with the end of the die 11'. Instead the carrier 10' is provided with a spring pressed stud which is denoted by numeral 25 and which is adapted to engage 105 in rounded recesses 26 in the bottom of the die 11'. The screw 12' of course sustains the die 11' during the threading operation and the stud 24 engaging the recesses 25 causes the die to recede with its carrier. 110

The invention eliminates a multiplicity of parts likely to get out of order. No chips can obstruct the operation of the tool and upon the completion of one piece of work it is unnecessary to "back thread" 115 which operation is very hard on the die teeth besides taking up considerable time.

What I claim as new and desire to secure by Letters Patent is:—

1. The combination with a diestock having a work receiving opening and a slideway communicating therewith; of a die supporting member arranged in said slideway, a die removably carried by said member and adjustable relatively thereof, a boss carried by said die supporting member, a screw threaded through said boss and engaging said die for actuating the same in the direction of the work, said screw constituting a stop for sustaining the die in the threading 130

operation, the shank of said screw adjacent its head being unthreaded and having a plurality of circumferential grooves spaced to exactly agree with the ratio of difference in 5 the diameters of standard sized work, and means selectively engaging said grooves to prevent movement of said screw to thus maintain the die in position to thread work of a predetermined diameter.

10 2. The combination with a diestock having a work receiving opening and a slideway communicating therewith; of a die supporting member arranged in said slideway, a die removably carried by said member and 15 adjustable relatively thereof, a boss carried by said die supporting member, a screw threaded through said boss and engaging said die for actuating the same in the direction of the work, said screw constituting 20 a stop for sustaining the die in the threading operation, the shank of said screw adjacent its head being unthreaded and having a plurality of circumferential grooves spaced to exactly agree with the ratio of difference 25 in the diameters of standard sized work, an adjustable stop carried by said screw to selectively engage in said grooves whereby to engage the end of said boss when the screw is tightened to limit inward movement 30 thereof, and said stop being adapted to bind against said boss and the walls of the groove in which it is positioned to restrain said screw against rotation.

35 3. The combination with a diestock, its dies, and screws threaded through tapped bosses and engaging the dies for moving the same toward the work; of each screw having a plurality of spaced transverse grooves, an abutment selectively positionable 40 in said grooves, said abutment being adapted to bind against said boss and the walls of said grooves when the screw is tightened to restrain the same against movement.

4. The combination with a diestock, a die member, and a die actuating screw interposed between said die member and a fixed member, one of said members being tapped to receive said screw, the latter constituting an adjustable stop for variably spacing said members; of an adjustable abutment, said screw having a plurality of spaced transverse grooves into which said abutment is freely positionable, and said abutment being designed to engage and bind in said grooves when brought to bear against said tapped member.

5. In a diestock, a die carrier for each die on which the dies are relatively adjustable for variously sized work, a boss formed upon each of said carriers and forming a fixed stop for its die, a screw working in said boss and sustaining its die against outward movement in the thread cutting operation, each screw having a plurality of longitudinally spaced recesses therein, and means 60 engaging in said recesses and against said boss for determining the proper position of said screw for threading work of a predetermined size.

6. In a diestock, a die carrier for each die on which the dies are relatively adjustable for variously sized work, a boss formed upon each of said carriers and forming a fixed stop for its die, a screw working in said boss and sustaining its die against outward movement in the thread cutting operation, each screw having a plurality of longitudinally spaced recesses therein, and means 70 engaging in said recesses and against said boss for determining the proper position of said screw for threading work of a predetermined size, said last named means binding against said boss to lock said screw against movement.

In testimony whereof I affix my signature.
